UNITED STATES PATENT OFFICE.

JOHN E. KALGREEN, OF MINNEAPOLIS, MINNESOTA, ASSIGNOR TO J. R. CLARK COMPANY, OF MINNEAPOLIS, MINNESOTA, A CORPORATION OF MINNESOTA.

IRONING BOARD.

Application filed June 5, 1923. Serial No. 566,093.

The object of this invention is to provide an ironing board that is light in construction, using a minimum of material, and at the same time, when set up, is absolutely rigid and will not rock, sway or swag when in use.

Other objects of the invention will appear from the following detailed description.

The invention consists generally in various constructions and combinations, all as hereafter described and particularly pointed out in the claims.

In the accompanying drawings forming part of this specification,

15. Figure 1 is a side view of an ironing board embodying my invention,

Figure 2 an end view of the same,

Figure 3 is a bottom view of the board folded,

20. Figure 4 is a detail view of one end of the board, showing the manner of hinging the legs thereon, taken on the line 4-4 of Figure 1,

Figure 5 is a sectional view on the line 25 5-5 of Figure 4,

Figure 6 is a detail sectional view showing the yielding button or plug in the end of the center leg of the board,

Figure 7 is a detail view showing the manner of connecting the braces with the legs.

In the drawings, 2 represents the top or table portion of the board, having cross pieces 3 and 4 secured transversely to the underside thereof by screws or other suitable means. 5 is the main or center leg of the board, having a pivot 6 at one end, mounted in ears 7 that are secured to the board. This leg lies centrally against the underside of the board when folded and assume an inclined or oblique position, as indicated in Figure 1, when the board is set up. End legs 8 are provided, having pivots 9 at one end on a yoke 10 which has angled end portions 11 pivoted at 12 to ears 13 secured to the under-

45 side of the board. The pivots 9 and 12 are at right angles substantially to each other and form in effect a universal joint for the legs 8, allowing them to swing lengthwise of the board and laterally thereof. Braces 14 have a pivotal connection at 15 with an ear 16 that is secured to the middle portion of the cross bar 3 and said braces diverge from their point of pivotal connection with the ear 16 and are connected by pivots 17 with

50 the legs 8. The ends 18 of the braces are in-

wardly turned to form an offset and wires 19 are connected to these ends and have their opposite ends interlocked or intertwined with the wire 20 that is folded upon itself in the form substantially of a narrow U, 60 the loop of which is seated in a notch 21 in the end of the center leg 5. The direct connection of the wires to the ends of the braces insures a very rigid frame and entirely eliminates the danger of splitting the wooden 65 brace bars which often happens when the tension wires are attached to the eyes 24. The opposite end of this leg 5 has a yielding button 22 therein, preferably of rubber, that is adapted to bear on the underside of 70 the board when the legs are unfolded and yield slightly under pressure and allow the braces to be inserted in their proper position and take up the slack or lost motion in the joints or bearings of these braces. 75 The brace members and the legs are locked in their unfolded position and rigidly held by means of brace bars 23 which have metallic ears 24 riveted thereto at one end, said ears being pivoted at 25 to the offset 80 ends 18 of the braces 14. The brace bars 23 converge from their points of connection with the ends 18 and near their opposite ends have a connection 26 between them consisting preferably of a section of wire which 85 bridges the gap between the bars and has its ends seated therein. The extreme ends of the bars 23 are beveled and are adapted to bear against the underside of the board and the cross bar, the brace bars being of such 90 length that when the legs are unfolded and the ends of the bars placed in contact with the cross bar 4, the wires 19 and 20 will be under tension, as well as the braces 14, and the longitudinal pressure of the brace bars 23 95 will exert a sufficient pull on the center leg 5 to compress the button in the end of this leg and take up all lost motion in the joints and pivots of the leg, so that the board will be extremely stable and rigid when in 100 use. When the board is folded, the legs and braces will lie down flat thereon, as indicated in Figure 3, and allow the board to be packed in very small compass, thereby economizing space in transportation.

105 I claim as my invention:

1. An ironing board comprising a top, a pair of legs pivotally connected thereto near one end, braces pivotally connected to said top between the pivotal connection of said 110

- end legs and that end of the board near which said legs are connected and secured to said end legs at points remote from their pivotal connections, and having offset end portions near their connections with said end legs, a center leg pivotally connected at one end to said top, means connecting the offset end portions of said braces with the lower end of said center leg, brace bars having pivotal connections with the offset end portions of said braces and having at their upper ends a bearing on the under side of said top.
2. An ironing board comprising a top, a pair of legs pivotally connected thereto near one end of said top, braces pivotally connected to said top adjacent to the same end, near which said legs are connected and secured to said legs at points remote from said pivotal connection, said braces having offset extensions, a center leg pivotally connected to said top near one end, and bearing against the under side of the board to take up lost motion between the board and center leg, brace bars having ears secured thereto at one end and pivotally connected with the offset extensions of said braces and having opposite ends adapted to engage the under-side of said board, and tension wires engaging said center leg at the end remote from its pivotal connection and connected to said braces between the pivotal connection thereto of said brace bars and the point of securing said braces to said end legs.
3. An ironing board comprising a top, end legs, and braces therefor having pivotal connections with each other and with said top, a center leg pivotally connected near one end with said top, tension means connecting the lower portion of said center leg with said end legs, brace bars pivotally interposed between said end legs and said top for applying longitudinal stress to said tension means and center leg, and a yielding device interposed between the end of said center leg and the under surface of said top and put under tension by the placing of said brace bars in their working position to take up lost motion in the pivotal connections of said legs and braces.

In witness whereof, I have hereunto set my hand this 31st day of May, 1922.

JOHN E. KALGREN.
